(57) **CLAIM**

The ornamental design for a net light, as shown and described.

DESCRIPTION

FIG. 1 is a front elevational view of a net light showing my new design;

FIG. 2 is a rear elevational view thereof;

FIG. 3 is an enlarged view of portion 3 shown in FIG. 2;

FIG. 4 is an enlarged view of portion 4 shown in FIG. 2;

FIG. 5 is a perspective view thereof;

FIG. 6 is an enlarged view of portion 6 shown in FIG. 5; and,

FIG. 7 is an enlarged view of portion 7 shown in FIG. 5.

The broken lines show the boundaries of the enlarged views and form no part of the claimed design.
